UNITED STATES PATENT OFFICE.

THOMAS J. OWEN, OF CHICAGO, ILLINOIS.

AUTOMATIC PLATE-CHANGING MECHANISM.

1,187,776.

Specification of Letters Patent. Patented June 20, 1916.

Application filed May 19, 1913, Serial No. 768,402. Renewed November 15, 1915. Serial No. 61,723.

To all whom it may concern:

Be it known that I, THOMAS J. OWEN, a citizen of the United States, residing at Chicago, in the county of Cook and State of Illinois, have invented certain new and useful Improvements in Automatic Plate-Changing Mechanism, of which the following is a specification.

My invention relates to automatic plate-changing mechanism for presenting plates or slides to picture-projecting apparatus and like uses.

One of the general objects of my invention is to provide an automatic plate changer which may handle a large number of individual plates, presenting them, in predetermined order, in position for display, and capable of continuing its operation indefinitely to present the series over and over.

A further object of my invention is to provide an automatic plate changer in which the plates move always in the same horizontal plane.

Another object of my invention is to provide the automatic plate-display mechanism in a simple, small, compact construction particularly adapted for installation in shallow spaces, and for easy portability. For instance, a device constructed in accordance with my invention may be installed in the relatively shallow roof space of a street car for advertising display or projecting purposes, so that the stereopticon may throw its exposed pictures upon a screen at the end of the car, or it may easily be carried about by a lecturer for use in changing the views used to illustrate the lecture; or, built on a scale for carrying larger plates, it may be used for show window advertising for direct display of pictures or advertising matter, or used with sensitized plates in an appropriately darkened housing, the device might be employed as a camera plate-changer.

Another object of my invention is to provide such construction that the number of different kinds of parts employed may be minimized and many of the operating parts be made duplicate one of the other.

Other and further objects of my invention will become apparent from the following description.

In the drawings, wherein I have illustrated an embodiment of my invention, Fig. 1 is a plan view of the machine with parts

broken away; Fig. 2 is an end elevation of one end of the machine, showing only one of its series of similar operating cam levers to avoid confusing multiplicity of lines; Fig. 3 is a section on line 3—3 of Fig. 2 of the left hand magazine. Fig. 4 is a section on line 4—4 of Fig. 1. Fig. 5 is a diagram of the main shaft to show its cam-time. Fig. 6 is a detail of a plate. Fig. 7 is a section on line 7—7, Fig. 1. Fig. 8 is a detail section on line 8—8, Fig. 1.

For convenient handling, uniformity of size, and for durability, the plates P (Fig. 6), used in my machine are preferably framed in (one piece) metal rims R, with the side edges of the rims, at their corners, tapered as at r.

Throughout the following description I will refer to the part of the machine carrying the motor, as its front.

The specific machine shown in the drawings has two plate magazines 10 and 10', and all parts and mechanisms for the magazine 10 are duplicated, in effect, in the magazine 10'. Like parts in magazine 10' are indicated by the same numerals applied to parts in magazine 10, differentiated by the exponent prime ('). Magazine 10 is divided into two compartments 11 and 12 by a partition 13, extending fore and aft, and shorter than the compartment, so that beyond the ends of the partition 13 there are left passages 14 and 15 through which plates may be passed edge-wise, or transversely, one at a time, from one compartment to the other. The two magazines are spaced apart to leave between them a display space 16, bridged, in alignment with the front passage ways 14—14', by a plate-guide 17, or display structure, long enough to permit the exposure of a plate therein between the magazines, said plate guide (Fig. 7) having top and bottom rails 18 and 19, flanged to aid in holding the plate erect. The plate receiving display space defined by the appropriate guiding instrumentalities is common to the two magazines—that is, it serves both, receiving plates from either magazine. Thus, generally speaking, the machine, from end to end, or transversely, may be regarded as divided into five units of length, each of which may be regarded as approximating, roughly, the length of one plate. Of these five units of space the center units is the plate-display space; the extreme units or compartments 12—12' are the delivery

100
105
110

spaces from which plates are supplied for presentation to the display space; and the intervening units or compartments 11, 11' are plate-receiving spaces, into which the 5 plates are returned after they have been displayed.

The general idea of plate movement for which I provide, is: (1) A plate delivered from the left-hand compartment 12, say, is 10 carried through the front passage way 14 and into the plate guide 17, pushing out of said guide-way a previously displayed plate and forcing said previously displayed plate into the receiving compartment 11' of the 15 right hand magazine; (2) the whole body of plates in the said receiving compartment 11' is moved backward to remove the returned plate from the front passageway, 14'; (3) the rearmost plate in compartment 20 11' is transferred through the passageway 15' into the delivery compartment 12'; (4) the whole body of plates of said compartment 12' is moved forward to bring the forwardmost plate into the front passage 25 way 14'; (5) the last said plate is moved through the front passage-way 14' to display position, in plate guide 17, returning the previously displayed plate back into the receiving compartment 11 of the left hand 30 magazine. Obviously, now, when the mechanisms of the left hand magazine 10 repeat the sequence of actions thus described with respect to the right hand magazine, another plate from the left hand delivery compartment 12 is presented for display; and so on, 35 throughout an endless series of operations.

The instrumentalities which I have shown for effecting the plate movement are three in kind: a double slide-carrier for carrying 40 plates from the delivery compartments to the display space, single slide-carriers for transferring plates from the receiving compartments to the delivery compartments, and screw conveyers for moving the plate-packs 45 within the several compartments.

A double slide or plate carrier 20 operates in conjunction with the front passage ways 14, 14' and guide way 17, alternately to move plates from the respective 50 delivery compartments 12 and 12' to the display space. This double slide-carrier may be regarded as occupying three units of length of the machine and at its extremities it has plate-engaging lips 21 and 21' for 55 moving plates in said lengthwise passageways 14 and 14'. Its range of reciprocation may be regarded as two units of length of the machine, so that as one lip, say 21, carries a plate from compartment 12 to the 60 exposure space 16, the other lip, 21', may move from the position shown in Fig. 1 to the remote end of delivery compartment 12'.

For transferring plates within each magazine from the receiving compartment 11 to 65 the delivery compartment 12, I preferably

employ a "single" slide carrier 23, having a single lip 24 at its end which is toward the receiving compartment. This slide carrier, working through a range approximately equal to one unit of length of the machine, 70 functions to transfer plates one at a time through the rear passage-way 15 from the receiving compartment to the delivery compartment.

As a suitable means for conveying plates 75 flatwise, forward in each delivery compartment and rearward in each receiving compartment, I provide screw conveyers, the conveyer for each compartment preferably consisting of three screws, two at the bottom 80 and one at the top. The screws 25 (Fig. 3) in the delivery compartment 12 work to feed the plates therein forward; the screws 26 in the receiving compartment work to feed the plates therein backward. 85

When the machine is to be operated to display the maximum number of plates that it is capable of handling, the conveyers for all four magazine compartments are loaded with plates to the full depth of their partition walls, 13 and 13', and one additional plate for each magazine 10 and 10' is provided. As shown in Fig. 1, the added plate P¹, for magazine 10' is displayed in the 90 guide-way 17 bridging the display space 16; and the additional plate P² for the magazine 10 is lodged against the lip 21 of the double slide carrier 20, which stands at the left hand end of its range of throw. Now by appropriate sequence of movements the plate-conveying parts of the machine work through a cycle as follows: First; double-slide carrier 20 moves to the right, through 95 passage-way 14 carrying plate P², which pushes plate P¹ out of display space 16 and into the front passage-way 14' until it alines, fore-and-aft, with compartment 11', plate P² replacing plate P¹ in display space 16. Second; screws 26' operate, carrying 100 their load of plates rearwardly and bring the rear-most plate (say P²⁵) into the path of single slide carrier 23'. Third: slide carrier 23' moves from compartment 11' to compartment 12' carrying said plate P²⁵ into delivery compartment 12' and into the 105 range of operation of the screws 25', (while slide 23 for the other compartment moves idly to position registering with compartment 11. Fourth: screws 25' carry their load of plates forward, moving plate P³ into the front passage-way 14' with its edge presented for engagement by the lip 21' of the double slide carrier 20. Fifth: the double slide carrier 20 performs its return movement, carrying plate P³ to display space 16 110 and thereby forcing plate P² back into alinement with compartment 11. Sixth: conveyer screws 26 operate, carrying the plate pack in receiving compartment 11 back and said plate P² out of the front passage- 115

120

125

130

way 14 and presenting the rearmost plate of the load (say P^2) in the path of slide carrier 23 (which had been previously moved to the right hand end of its throw). 5 Seventh: slide-carrier 23 moves from right to left carrying plate P^2 to compartment 12. Eighth: screws 25 carry forward their load of plates, bringing plate P^1 forward into the range of movement of the double 10 slide-carrier—that is to say, into position originally occupied by plate P^2 , thereby completing a cycle of operation of the machine. During this cycle two plate-changes or exposures have taken place. Each plate, 15 it will be observed, is exposed for substantially half of the cycle of machine operation (less the time of actual substitution while one plate is pushing the other from exposed position). Thus there is no material interval of idleness in the plate-display sequence. Were the display space 16 made exactly the length of one plate the machine might be used for half of its full capacity, only one magazine being filled 20 initially. Under such circumstances, as will plainly be apparent, the same cycle of operation as heretofore described would result in the plates being fed one at a time from the full magazine into the empty 25 magazine, each plate being exposed during a full cycle instead of a half cycle of machine operation. When all of the plates were fed into the empty magazine they 30 would then commence to be fed back into the magazine in which they were first contained, and so on.

When the machine is built for use only with the two magazines alternately supplying plates, I prefer, as a refinement of construction, to use a plate-centering device to locate said plates accurately in the slide-way 17. To this end the slide-way is made somewhat longer than a plate, the upper and lower rails 18 and 19 of said slide-way 40 being longitudinally slotted and engaged by pins 28 on a vertical block 29, preferably of wood or other suitable material which has a limited range of motion between the ends of the slots. This centering block 29 should be of a width equal to half the 45 excess length of the bridge 17, and manifestly said block is always interposed between the approaching plate and the plate being removed from exposure, the positive limitation 50 upon the range of movement of said block insuring that every plate is exactly centered in the exposure space and may not be thrown past central position by its momentum.

60 In mechanical construction each magazine may conveniently be formed of three vertical frame-plates, suitably interconnected, and indicated as a back plate 30, front plate 31, and face plate or bearing 32. Plates 30 and 31 may be connected by suitable top

and bottom wall sections, 33 and 34, spaced apart a distance substantially equal the height of a display plate, and suitably separated lengthwise of the machine to receive the conveyer screws for the corresponding 70 compartment. The top and bottom walls are vertically connected by the partition 13. The slide-way for the double slide carrier 20 is provided by two appropriately channeled strips 36 secured to the rear surface 75 of the front plate 11 as best shown in Fig. 2, the double slide carrier 20 itself being merely a rectangular frame work of metal, sliding in said way, carrying the lips 21 and 21' in position extending into the front passage-way, 14—14 for the plates, and preferably having its lower rail provided with a rack 37, for a purpose to be described. A display plate or slide P, when moved into coöperation with the double slide carrier 20 80 merely rests flat-wise against the rectangular frame of the carrier with the end of the plate engaged by the appropriate lip. As each conveyer screw is given a complete rotation every time it is operated, all screws 85 normally stand with their inter-thread spaces alining transversely or from end to end of the machine so that when a plate is moved edge-wise by the double slide carrier it passes across the bodies of all screws in 90 its path, the tapered corners r of the plate frame R guiding it neatly into the inter-thread spaces. The weight of the plate is carried by the screw bodies and the bottom walls of the compartment until it slips onto 100 the lower rail 19 of the guide-way 17. The plate guide-way 17 is in substance a continuation of the top and bottom walls of the reservoir across the exposure space 16, the rails 18 and 19 being inturned or flanged 105 sufficiently to hold the plate erect, flat against the slide carrier 20.

To prevent a plate, when pushed into the passage way 14, from being thrown too far, I provide a one-way latch 38 (Fig. 8) working through an opening 39 in the top wall 33 of the magazine.

The single slide-carrier 23 may conveniently be a flat plate having its end bent to form lip 24, said plate slidingly guided in two rails 40 mounted on posts 41 secured to the back plate 30 so that said rails are spaced apart somewhat from said plate to leave room for the mounting of gearing to be described, said plate 23 carrying on its 115 rear face a rack 42.

With a view to simplicity, economy in construction, and compactness of the machine, I have devised a special driving arrangement for coöperation with the organized parts heretofore described wherein all of the essential movements in the cycle of operations first described may be obtained from a series of identical cam-levers driven by studs on a main shaft. 125

In the construction shown, the base plate 43, on the rear portion of which the magazines are mounted, carries suitable brackets 44 to receive the shafting, said brackets secured to face plate 32 and to the base 43. In order that the center portion of the machine may be free from obstruction by lengthwise shafting four such brackets are provided and the main shaft 45 is divided into two sections, each about the length of a magazine, and interconnected for rotation in unison by spur gears 46 on said shafts meshing with pinions 46' on a jack shaft 47 extending lengthwise of the machine near the base plate, out of the way of the light-projecting apparatus. One of said gears 46 receives power from a pinion 48 connected with a worm wheel operated by worm 48' which may conveniently be driven by a small electric motor 49 or any other suitable source of power. The cam levers are all pivotally mounted on the shaft 50 at the front of the brackets and for the seven operating mechanisms described there are provided the seven similar cams numbered in the order of their sequential operations 51, (for operating the double slide carrier), 52 (for operating screws 26'), 53 (for operating single slide carrier 23'), 54 (for operating screws 25'), 56—(for operating the screw conveyer 26—after the cam 51 has returned the double slide carrier), 57 (for operating the single slide carrier 23), and 58 (for operating the screws 25).

Each cam lever, as shown in Fig. 2, comprises a lever arm 60 extending forward below the main shaft 45 into proximity to the face plate 32 and a cam-rim portion 61 encompassing the main shaft 45. This rim portion has its bearing face, defining the center opening, struck on two arcs, which, when the lever is in different positions of its oscillation about its pivotal axis 50, are respectively concentric with the shaft 45, the upper and lower arcuate surfaces 62 and 63 being connected by clearance recesses 64, so that the opening is somewhat of lemon-shape. The main shaft 45 carries within each said cam-rim a stud 65 having a radial length equal to the radius on which the arcuate surfaces 62 and 63 are struck, so that rotation of the stud 65 within the cam-rim from the position shown in Fig. 2 produces a dwell, as long as the stud rides on the arcuate surface 62, a quick depression when the stud passes through the clearance 64 and rides against the arcuate surface 63; another dwell as it passes over the arcuate surface 63; and a rise as the stud rides back under the arc 62. Manifestly each cam lever, therefore, makes every movement from one extreme to the other rapidly, (preferably within 45 degrees of shaft-rotation) its up and down movements alternating and occurring at time intervals of 180° of rotation.

of the main shaft. The relative timing of the operation of the several cams, therefore, is merely a matter of the setting of studs 65 with respect to the main shaft. A proper setting for the machine herein shown is diagrammatically illustrated in Fig. 5, cams 52, 54, 56 and 58 doing their effective work on the up-stroke; cams 53 and 57 doing their work on the down-stroke.

The rear end of each cam lever carries a pin 66 engaging a horizontal slot 67 in an ear 68 projecting from an appropriate vertical rack through a vertical slot provided therefor in the face plate 32, the seven racks corresponding with the cams being all appropriately guided in the space between plates 31 and 32. Only the racks associated with magazine 10 are shown, these being indicated by numerals 71, 76, 77 and 78, corresponding with the cam numerals 51, 56, 57, and 58. Rack 71 works through a suitable multiplying gear 79 to drive the rack 37 of the double slide carrier 20 back and forth to its full limit of throw, in obvious fashion.

Rack 77 for driving the single slide carrier 23 operates through a suitable multiplying gear 80 between the plates 31 and 32 to drive a shaft 81, which extends over the wall 33 to the rear plate 30, said plate carrying a train of gearing 82 receiving motion from said shaft and serving to drive the rack 42 forming part of the single slide-carrier structure.

Rack 76 serves to rotate in appropriate direction the upper screw 26, and to this end operates multiplying gearing 83 to drive a gear 84 which is loose on the spindle of the screw 26.

There is a one-way ratchet wheel 85 fixed on the spindle of screw 26, coöperating with the pawl 86 carried by said gear wheel 84, so that only on the upward movement of rack 76 is the screw (26) rotated, the downward movement of the rack merely causing gear 84 to rotate idly without rotating the screw. For communicating motion to the two bottom screws of the three, which should rotate in unison, I mount on the back plate a large gear 87 meshing with pinions 88 on the shafts of all three screws, said gear 87 also coöperating with a pawl 89 which prevents reverse rotation of said gear.

Exactly similar provision is made for driving the screws 25 from the rack 78, save that the direction of rotation of the screws is reversed, as will be noted, Fig. 4.

It will be apparent with the construction described, I am enabled to use short vertical racks, and by proper proportioning of the reduction gear to secure therefrom exactly the desired range of movement of the respective plate handling parts, at the same time keeping the vertical height of the machine within such small compass that the de-

vice may be installed in a very shallow space, such as a car roof space.

It will be understood, of course, that suitable light-projecting apparatus of any desired construction may be associated with the plate-changer for projecting the picture displayed in the space 16 upon a suitable screen, but such projection apparatus may be of any desired character and therefore is not shown. Its condensing lenses would be in front of the bridge 17, its focusing lens in rear thereof.

While I have herein described in some detail a particular embodiment of my invention it will be apparent to those skilled in the art that many changes might be made in the specific construction without departure from the spirit of my invention and within the scope of the appended claims.

20. What I claim is—

1. Apparatus of the character described, comprising, in combination, two magazines separated by an intervening display structure and automatic means for moving plates singly in opposite directions from either magazine into the same display structure.

2. Apparatus of the character described, comprising, in combination, two magazines separated by a single intervening display structure and automatic means for presenting plates from said magazines alternately in said single display structure.

3. Apparatus of the character described, comprising, in combination, two magazines separated by an intervening display space, and automatic means for presenting plates from said magazines alternately in the same position in said display space in endless succession.

40. 4. In a machine of the character described, the combination of two magazines, each divided into compartments, said magazines separated by a display space, and means for delivering plates singly from a relatively remoter compartment, of either magazine, to the display space, and, through the delivered plate, pushing the previously displayed plate into a less remote compartment of the appropriate magazine.

50. 5. In a machine of the character described, the combination of two magazines, each divided into two compartments, said magazines separated by a display space, and means for alternately delivering plates singly from the relatively remoter compartment, of said magazines to the display space, and, through the delivered plate, pushing the previously displayed plate into the less remote compartment of the appropriate magazine.

60. 6. In a machine of the character described, the combination of two magazines separated by an intervening display space, each magazine divided into a plurality of compartments, means in connection with

each magazine for feeding plates through the compartments thereof from a compartment adjacent the display space to a compartment remote therefrom, and means co-operating with the respective magazines for carrying plates from said remote delivery compartments of the two magazines, alternately, to the display space.

7. In a machine of the character described, the combination of two magazines separated by a display space, each magazine divided into a plurality of compartments including a delivery compartment, means connected with each magazine for feeding plates in appropriate directions flat-wise through each said compartment and edge-wise from compartment to compartment, and means co-operating with both magazines for transferring plates from their delivery compartments to the display space.

8. In a machine of the character described, the combination of two magazines spaced apart, each divided into two compartments, laterally communicating at their front and rear ends, a guide-way bridging the space between said magazines and aligning with the front passages between compartments of said magazines, means for moving a plate from either outermost compartment to said guide-way, means for feeding plates flat-wise through said compartments of each magazine in opposite directions, and means for transferring plates singly from the inner-most to outer-most compartments.

9. In a machine of the character described, the combination of two plate magazines, spaced apart to afford an intervening display space, a plate guide-way bridging said display space, means dividing each magazine into two compartments communicating laterally at their front and rear ends, plate carrying screws for each compartment for feeding the plates flat-wise through each compartment in appropriate direction, a slide carrier local to each magazine for feeding plates singly from one compartment to the other, and a double slide-carrier common to the two magazines, co-operating with the plate display slideway and arranged to deliver plates from either magazine into said slide-way.

10. In a device of the character described, two magazines separated by a display space, a plate guide spanning said display space, means for delivering plates from said magazines alternately to said plate guide, and a centering stop movably carried by said plate guide in the path of plate movement and having a limited range of movement in said plate guide.

11. In a device of the character described, two magazines separated by a display space, a plate guide spanning said display space, means for delivering plates from said maga-

zines alternately to said plate guide and a centering strip interposed in the path of movement of the plate approaching said guide and having a range of movement appropriate to center the plate in said plate guide.

12. In a machine of the character described, the combination, in a plate magazine, of a frame, a partition dividing said frame into two compartments, said two compartments being transversely open to each other beyond the opposite ends of the partition, conveyer screws associated with each compartment for moving plates bodily flatwise in the compartment, a slide carrier working in a space beyond the partition for transferring plates from one compartment to the other, and operating means for said plate moving devices.
13. In a machine of the character described, means providing a plurality of compartments, a plurality of plate moving means for conveying plates through said compartments and transferring them from one compartment to another, operating devices for said plate moving means comprising a power shaft, a plurality of operating studs on said power shaft, and a like plurality of similar cam levers actuated by the studs and respectively connected with said several plate moving means.
14. In a machine of the character described, means providing a plurality of compartments, a plurality of plate moving means for conveying plates through said compartments and transferring them from

one compartment to another, operating devices for said plate-moving means comprising driving racks, and driving means for said racks comprising a power shaft, a plurality of operating studs on said shaft, and a like plurality of cam-levers connected with said racks, said cam-levers surrounding the power shaft and coöperating with studs thereon and each providing two arcuate surfaces of equal radius.

15. In a machine of the character described, a plate magazine divided into two compartments, a conveyer associated with each compartment for feeding plates flatwise through the compartment in appropriate directions, slide carriers for transferring plates from one compartment to the other, and driving means therefor comprising horizontal racks for the slide carriers, vertical racks to receive power, and gear connections between said vertical and horizontal racks.

16. In a machine of the character described, the combination of a frame, plate conveying screws for moving plates flatwise in said frame, means for moving plates transversely across said screws and plates having their corners tapered for guidance in the inter-thread spaces of the screws.

In testimony whereof I hereunto set my hand in the presence of two witnesses.

THOMAS J. OWEN.

In the presence of—
GEO. T. MAY, Jr.,
MARY F. ALLEN.
